AUTOMOBILE JACK

Carl W. Johnson, Glencoe, and Gilbert M. Smith,
Congress Park, Ill.; said Smith assignor to
said Johnson

Application March 25, 1935, Serial No. 12,766

3 Claims. (Cl. 254—97)

Our invention contemplates and provides a novel and improved jack adapted to be applied to the bumper of an automobile and to be operated with ease and facility by a person standing clear 5 of the vehicle.

Our jack, in its preferred embodiment herein described and claimed, comprises a rack-bar which is detachably received and supported by the upper end of a standard which in turn has 10 its lower end articulated in a suitable base. Embracing the rack-bar, and vertically movable with respect thereto, is a gear housing provided with bifurcations for the reception of bumper bars, or bumper bar brackets, of different thicknesses. Vertical movement of the gear housing 15 on the rack-bar is accomplished by rotation of a spur gear which is permanently in mesh with the rack-bar and adapted to be driven up or down the rack-bar through the agency of a worm gear 20 and its co-operating worm,—the said worm operating on an axis inclined to the horizontal and being arranged for detachable cooperation with a wrench held and operated by a person standing alongside the jack and away from the vehicle to be lifted.

Other features, objects and advantages of our invention will appear from the following detailed description, wherein reference is made to the accompanying drawings, in which—

Fig. 1 is an elevational view illustrating our improved jack applied to the rear bumper bar of an automobile of modern design;

Fig. 2 is a side view of the jack in which certain parts of the structure are broken away 35 for clearness in illustration—the gear housing section in this figure being taken on the line 2—2 of Fig. 3, and looking in the direction indicated by the arrows;

Fig. 3 is a front view of the jack in which certain parts of the structure are shown in section;

Fig. 4 is a rear elevational view of the gear housing and a fragment of the rack-bar, which view may be regarded as taken from the plane of the line 4—4 of Fig. 2, and looking in the 45 direction indicated by the arrows;

Fig. 5 is a fragmentary sectional detail view taken on the line 5—5 of Fig. 4, and looking in the direction indicated by the arrows;

Fig. 6 is a horizontal sectional view taken on the line 6—6 of Fig. 3, and looking in the direction indicated by the arrows; and

Fig. 7 is a sectional detail view taken on the line of 7—7 of Fig. 2, and looking in the direction 55 indicated by the arrows;

Similar characters of reference refer to similar parts throughout the several views.

As illustrated in the drawings, our jack comprises a rack-bar 10 provided with a lower end portion 11 for detachable reception in a correspondingly shaped receptacle 12 formed in the upper end of a vertical standard 13. It is preferred that the rack-bar portion 11 and its receptacle 12 be circular in transverse section, as shown, so that the former may be turned in the latter as the hereinafter mentioned gear housing is being propelled upwardly on the rack-bar. The rack-bar is also preferably provided with an integral flange 14 which rests on the top of standard 13.

The lower end of the standard 13 is articulated, by the heavy pivot pin 15, to and between the upstanding spaced flanges 16—16 of the base 17,—the arrangement being such that the bottom of the base may be swung into parallelism 20 with one of the longitudinal surfaces of the standard for convenience in packing the jack into a tool box.

Embracing the rack-bar 10 is a vertically movable two-piece gear housing 18 which is provided with aligned rectangular openings 19 and 20 through which the rack-bar slidably extends. The two parts of the gear housing are joined in a plane which includes the axis of the worm presently to be mentioned, and are conveniently secured together by rivets 21, 21 extending through 25 abutting flanges 22, 22.

Journalled in the gear housing 18 is a horizontal shaft 23 to which is splined a spur gear 24, which is in mesh with the teeth of rack-bar 35 10. Also splined to shaft 23 is a worm gear 25, which is permanently in driven relation, and never in driving relation, to a worm 26, which in turn is splined upon shaft 27. Shaft 27 has radial and thrust bearings in the gear housing. 40

Attention is directed to the fact that the axis of worm shaft 27 is inclined to the horizontal, its lower end being concave for cooperation with the thrust bearing ball 28. Its upper end 29, which projects out of the gear housing, is of hexagonal or square cross section for cooperation 45 with the socket of a suitable wrench. Shaft 27 is preferably provided with an integral annular flange 30 to lie between the gear housing and a wrench socket applied to the portion 29 of the shaft.

That portion of shaft 27 which occupies its upper radial bearing is desirably provided with an annular groove 31, which is traversed by pin 55

32 to limit axial movement of shaft 27 relative to its bearings.

Formed integral with the rear face of the gear housing is an upwardly opening hook 33 arranged 5 to engage the lower edge of a bumper, or bumper bar bracket, to which the jack is applied. The inner surface 34 of the hook inclines downwardly toward the adjacent vertical surface 35 of the housing, so that the hook will readily accommodate 10 itself to bumper bars, or bumper bar brackets, of different thicknesses. If desired, the surface 35 of the gear housing may be provided with a rubber cushion 36 held in position by having integral frusto-conical lugs 37, 37, sprung 15 into correspondingly shaped apertures formed in that wall of the gear housing to which the cushion is applied. The cushion serves to prevent marring of an exposed finished surface of a bumper bar engaged by hook 33.

20 Formed integral with the top of the gear housing, is a heavy bifurcated lug 38 defining a V-slot 39 for the reception of bumper bars or bumper bar brackets of different thicknesses. Usually, in the use of the jack, the hook 33 is utilized 25 when a bumper bar is to be engaged, and the bifurcated lug is utilized when a bumper bar bracket is to be engaged.

At 40, in Fig. 1, we have illustrated a wrench having a socket for detachable cooperation with 30 the protruding portion 29 of the worm shaft 27.

The jack is most conveniently kept in a tool box with the rack-bar 10 and standard 13 disconnected, and with base 17 turned alongside one of the longitudinal surfaces of the standard 13.

35 When the jack is to be used, the base 17 is turned to the position shown in the drawings, and the lower end of the rack bar is fitted into the standard. The worm shaft 27 is now operated, by right hand turning of wrench 40, to 40 cause spur gear 30 to carry gear housing 18 upwardly on rack-bar 10 until either hook 33, or bifurcated lug 38, has embraced and accommodated itself to the lower edge of a bumper bar or bumper bar bracket.

45 While the gear housing is being moved upwardly on the rack-bar, it may be shifted laterally, around the axes represented by pin 15 and rack-bar portion 11, to steer either hook 33 or bifurcated lug 38, as the case may be, into alignment 50 and registry with the bumper bar or bumper bar bracket which said hook or lug is to engage.

We find that all necessary movements of the jack, after it has been assembled and placed in the substantially correct vertical position, may be 55 effected by manipulation of the wrench alone.

While the wrench 40 may be of the type having a socket provided with a ball plunger adapted to engage in recess 41 in the protruding portion 29 of the worm shaft 27, we achieve entirely satisfactory results when operating our jack with a wrench having a plain socket for reception of the worm shaft extremity 29. The fact that shaft 27 is inclined to the horizontal, makes it extremely easy to shift the jack housing to and fro, to get 65 proper alignment with the bumper bar or bumper bar bracket, by manipulation of the socket wrench engaging shaft portion 29, and without there being any necessity for the operator grasping any part of the jack proper.

70 After either hook 33 or bifurcated lug 38 has accommodated itself to either a bumper bar or bumper bar bracket, the bumper, and the portions of the automobile to which it is attached, are forced upwardly to the requisite height by 75 right hand turning of the wrench by an opera-

tor standing alongside the jack on the side thereof which lies away from the automobile.

Due to the fact that worm gear 25 and its associated spur gear 24 are always in driven relation, but never in driving relation, to worm 26, 5 the gear housing and automobile parts supported thereby are automatically locked in the elevated positions to which they are carried by right hand rotation of the jack wrench.

When the purposes of the jack have been 10 served, the wrench, being applied to the worm shaft extremity 29, is turned in the left hand direction until the gear housing has disengaged and cleared the bumper bar or bumper bar bracket to which it was applied. The rack-bar 10 may 15 then be removed from standard 13, the base 17 may be turned alongside standard 13, and the disassembled jack may then be put away, in a small space, in a tool box or the like.

It will thus be understood that we have provided a simple, sturdy and easily manipulated jack which is particularly suited to the jacking requirements of present-day automobiles which, with their knee action wheels, shortened chassis frames and overhanging bodies, render jacking 25 with old style jacks very difficult, unsafe and disagreeable and, in many cases, impossible.

When in the appended claims we mention a "bumper", we mean to include not only the impact bar thereof, but also the supporting brackets, usually of strap steel, by which the impact bar is attached to the body or chassis of an automobile.

What we claim is new and desire to secure by Letters Patent of the United States is:

1. A jack comprising a rack-bar of rectangular cross-section, a lower bar in alignment therewith of substantially the same length on which the rack-bar is mounted for rotation around its axis, a base whereon the lower end of the lower bar 40 is connected for pivotal movement on a horizontal axis, a housing having an opening similar in shape to said cross-section, mounted on the rack-bar for longitudinal movement thereon, a gear journaled by the housing and cooperating 45 with the teeth of the rack-bar to propel the housing along the rack-bar as said gear is rotated, non-reversible driving means for said gear comprising an element for engagement with and rotation by a suitable wrench, a worm mounted 50 on said element and a worm gear operable thereby to drive the said first gear, and a channel defined by the housing and opening toward that end of the rack-bar which lies away from the base, said channel being adapted to receive the 55 lower edge of a bumper bar and being capable of being brought into proper registry therewith by manipulation of the wrench utilized to actuate the gear driving means, the housing being capable of to-and-fro movement in one direction only and rotary movement about its axis.

2. A jack comprising a base, a riser in the form of a bar pivotally mounted on said base about a horizontal axis, a rack-bar of rectangular cross-section of substantially the same length mounted 65 on the upper end of said bar in alignment therewith so that it can rotate on said bar about its longitudinal axis, a housing having an opening similar to said cross-section mounted to travel on and longitudinally of the rack-bar, non-reversible propelling means carried by the housing cooperating with the rack-bar to effect movements of the housing longitudinally of the rack-bar, and said propelling means comprising an element arranged for cooperation with and ro- 70 75

- tation by a suitable manually actuated wrench, a worm mounted on said element, a worm gear in mesh therewith mounted in said housing and a gear operatively connected to said worm gear cooperating with said rack-bar, said housing being provided with a channel which opens without obstruction towards that end of the rack-bar which lies away from the base, whereby the operator, by manipulation of the wrench may steer said channel into alignment with the lower edge 5 of a bumper bar while the housing, by rotation of the same wrench, is being propelled upwardly toward that bumper bar.
- 10
3. A jack comprising a base, an intermediate supporting member pivotally mounted thereon for rotation in one plane only, and a rack-bar mounted on the upper end of said intermediate supporting member in alignment therewith and 5 for rotation thereon about its longitudinal axis, a housing slidably mounted on said rack-bar, operating means in said housing cooperating with the rack-bar for moving the housing up and down thereon, and means carried by said housing for engaging an article to be raised.
